VALVE SPRING LIFTER

Harry W. Kulp and Martin C. Dellinger, Lancaster, Pa., assignors to K-D Manufacturing Company, Lancaster, Pa., a corporation of Pennsylvania

Application March 23, 1933, Serial No. 662,332

7 Claims. (Cl. 29—86.3)

This invention relates to pry rod type valve spring lifters or compressors for use in the removal and replacement of the valve springs incident to the operation of grinding the valves of 5 automobile internal combustion engines, and is primarily intended for use in connection with the V-type of multiple cylinder engines.

In connection with at least one currently popular make of automobile having an engine of this 10 V-type, in order to grind the valves it is necessary to remove the valve springs from the motor block.

The primary objects of the present invention are to provide simple releasable means for positively gripping a helix of the spring in the jaw 15 whereby the spring will be positively held in said jaw until said means is released to the end that said spring may be certainly removed from place by the normal withdrawal of the lifter after the valve shall have been raised; to provide a tool 20 of this type with a protruding grip piece intermediate its ends to facilitate the manipulation of the tool; to provide a tool of this type in knock-down sections which may be disconnected for ease of packing in a mechanic's tool kit and which may 25 be rigidly connected to provide a long, solid, rigid pry lever; and to combine the grip piece with the knock-down feature in such way as to reinforce the joint between the separable sections.

In the accompanying drawings, in which we 30 have shown merely the present preferred form of our invention simply by way of illustration of the practice thereof, and with no thought or intention of being limited to the specific form shown:

Figure 1 represents a side elevation of a lifter 35 embodying our invention applied in operative position to lift a valve spring A of a V-type multiple cylinder internal combustion engine illustrated in phantom lines;

Figure 2, a top plan view of the lifter; 40 Figure 3, a view of the lifter partly in central longitudinal section and partly in side elevation;

Figure 4, a greatly enlarged fragmentary section on the line 4—4 of Fig. 2;

Figure 5, a fragmentary sectional view on substantially the same scale and in the same plane as Fig. 4, showing a spring gripped in the jaw and the operative relationship of the catch locking wedge and stop pin for the latter;

Figure 6, a greatly enlarged fragmentary detail sectional view of the lock operating element 18 and related parts;

Figure 7, a greatly enlarged fragmentary view in side elevation of the grip piece 3, the adjacent interlocking end portions of the sections 1 and 2 55 and associated parts;

Figure 8, a longitudinal central sectional view of the parts shown in Fig. 7;

Figure 9, an exploded view of the adjacent end portions of sections 1 and 2; and

Figure 10, a sectional view on line 10—10 of Fig. 9.

Referring now in detail to the drawings, 1 designates a preferably U-shaped channel sheet metal bar section having downwardly depending 10 manipulating or grip pieces or blocks 3 respectively swingingly engaging the respective outer side faces of the sides or legs of its rear end portion, the portions of said blocks or plates depending below the under surface of said section 1 being bent toward each other to lie face to face toward 15 each other and preferably being spot-welded together as indicated at 3' whereby the upper portions of said manipulating grip piece 3 will be held in snug sliding embracing and reinforcing engagement with said rear end portion of section 1.

A pivot pin 5 extends through the respective 20 sides of the section 1 and the plates 3 adjacent the forward end portions of the latter and extends across the space between the sides of the section 1 in spaced relation to the web or bridge thereof, and the extreme rear end portions of the sides of section 1 are formed with slots 7. A second section or handle lever 2 substantially of the same 25 length as section 1 has its extreme forward end portions of its side formed with slots 8 to receive in said slots the pivot pin 5 and carries a pin 6 so spaced from its inner end as to be received in the slots 7. As illustrated, the forward end portion of the section or handle 2 will preferably be inwardly offset so as to be received between the sides 30 of the rear end portion of the section 1, see Figs. 2 and 9.

The handle or manipulation piece 3 is swingably mounted on the rear end portion of the section 1 by the pivot pin 5 and is normally held up 35 against the lower face of section 1 by a helical tension spring 21 located in an opening in handle 3 and which has its lower end hooked into or connected to any suitable anchoring means such 40 as a lug 22 secured to and between the plates of handle or piece 3 by any suitable means, for instance by spot welding as indicated at 3', and has its upper end hooked into or connected to the lower end of a lug 23 having its shank threaded 45 downward through the web of the rear portion of section 1 and having an enlarged upper end portion resting on the upper face of said web so as to anchor the upper end of spring 21 to section 1.

The rear and upper portions of the plates comprising grip or handle 3 are formed with vertical slots 7' extending across the slots 7 when the grip 3 is in normal position as indicated in Figs. 7 and 9, the locking hooks or fingers 9 left between said slots 7' and the extreme rear edges of said plates extending substantially across the slots 7 to lock the pin 6 therein, and the rear upper edge portions of said hooks or fingers 9 being rounded as illustrated so that pressure thereon by the pin 6 will serve to swing the grip 3 downward about the pivot pin 5 against the opposition of spring 21 until the pin 6 moves forward in slots 7 and into the slots 7' and so beyond the hooks 9, when the spring 21 will swing the grip 3 up about its pivot pin 5 to normal position with the hooks 9 behind the pin 6 and so locking the same in slots 7.

The pin 6 will be formed with heads 6' and will be of such length that in the assembled relation of the tool the opposed faces of the heads 6' will be disposed laterally beyond the outer faces of the upper portions of the grip or handle 3 adjacent the respective slots 7' and hooks or fingers 9, and said pin 6 may be centered and held in centered relation by any suitable means, for instance by spring clips 24 straddling and resiliently gripping the pin 6, there being two such clips 24 employed as illustrated in Fig. 10, one engaging the inner face of one side or leg of the section 2, so that the pin 6 will be maintained in centered position to extend equally beyond each side face of the section 2.

The section 1 will have its forward end portion formed with a bifurcated jaw 4 to straddle the valve stem and engage between the helices of the spring or to engage under the lower helix of the spring, although usually it will be engaged between the helices of the lower portion of the spring and to facilitate the insertion of said jaw 4 between the adjacent helices of the spring, the extreme forward end edges or portions of the furcations of the jaw 4 will preferably be beveled down preferably to knife edges as illustrated in Figs. 3, 4 and 5.

The section 1 is preferably bent at a wide obtuse angle so as to depress its forward end downward beyond the plane of its rear end portion, although this is not essential, and similarly the section 2 is bent at a still wider obtuse angle so as to depress its rear portion below the plane of its forward portion, although this also is not essential.

A latch or gripping member 10 is secured by any suitable means, such as a rivet 12, to the section 1, and extends forward into and overlies the rear portion of the jaw 4 where it is provided with a rounded hook portion 11. This latch or gripping member 10 may be of resilient material, although this is not essential so long as there be provision for movement of the hook portion 11 toward and away from the opposed face of jaw 4. A rivet pin 13 passes through the sides of the forward end portion of the section 1 above the latch or gripping member 10 slightly to the rear of the hook portion 11. A wedge member or block 14 preferably normally extending below the pin 13 is adapted to be reciprocated between said pin 13 and latch or gripping member 10, and between the sides of the channel section 1 to lock the hook portion 11 of latch 10 over a helix of a spring A, as shown in Fig. 5, wherein the rear upper surface of the wedge member 14 is in tight engagement with the under face of the pin 13 and the extreme forward end of the lower face of the wedge member 14 is in engagement with the upper face of the latch 10 in a vertical plane in-

tersecting the gripped helix, although it is not essential that the wedge member 14 should engage the latch member 10 in a vertical plane intersecting the gripped helix, so long as the engagement is such as to firmly clamp the helix in the tool and prevent separation thereof therefrom until the wedge member or block 14 has been retracted to releasing position. In the construction shown the wedge block or member 14 is a resilient sheet metal member, but while this is preferred it is not essential, it simply being necessary that there shall be a wedge action and with this thought in mind any other means functioning in the same manner as the pin 13 may be substituted for the latter.

Any suitable means may be provided to reciprocate the locking wedge block or member 14 to move it forward to locking position and to move it rearwardly to releasing position. As one suitable means we provide a drag link or bar 15 pivotally connected at 16 by its forward end to the wedge member or block 14 and at its rear end portion similarly pivotally connected at 17 to and between the plates of the cam lever 18, which is pivotally mounted preferably adjacent the apex of the obtuse angle of the section 1 between the sides of the channel of the latter, the pivotal points 17 and 19 preferably being so related that in each of its extreme movements the pivotal point 17 will move beyond dead center with relation to pivot 19, so that when the wedge block 14 is shoved forward to locking position the pivot 17 will lie below and slightly in advance of the pivot 19, as shown in Fig. 6.

From the foregoing it will be apparent that when the parts are in the condition illustrated in Fig. 3, the jaw 4 may be forced between the helices of the lower portion of the spring A and that incident to that operation the rounded front side of the hook 11 will engage and ride up over one of the helices of the spring A which will then move backward into the jaw 4 until the hook portion 11 drops down in front of the portion of the helix, so interposed between the jaw 4 and latch 10, and that thereafter the movement of the lever 20 to the position indicated in solid lines in Fig. 6 will move the wedge block 14 to the locking position shown in Fig. 6 so firmly holding the spring in the jaw 4. Also that by moving the lever 20 to the position shown in Fig. 3 the wedge block 14 will be retracted to its extreme rear position, so releasing the latch 10 which may then yield upwardly if necessary in order for the rounded hook portion 11 to move out of the path of the gripped helix to permit the removal of the gripped spring A from said jaw 4.

Having thus described our invention, what we claim as new and desire to secure by Letters Patent is:

1. A valve spring lifter comprising a lever of substantially U-shape in cross section and having an end formed with a bifurcated jaw adapted to span the valve stem and to be inserted between the helices of a spring, in combination with a resilient latch permanently secured to the inner and upper face of the web of said lever and formed with a rounded forward downwardly presented hook portion at its forward end extending across a portion of said bifurcated jaw, said hook portion being adapted to ride up over and drop down behind a helix of the spring to hold said helix between the opposing faces of said jaw and said latch, a stop pin extending across the channel in said lever slightly to the rear of said jaw, a wedge block mounted for reciprocation between said

latch and pin and adapted to be moved to a position wherein it engages said stop pin with the rear upper portion of its wedge face and engages said latch in a vertical plane intersecting a helix of 5 a spring gripped between said latch and jaw, a cam plate pivotally mounted between the sides of said lever to the rear of said pin and a drag link pivotally connected at its respective ends to said wedge block and cam plate respectively to cause 10 the reciprocation of said wedge block in accordance with the movement of said cam plate.

2. A valve spring lifter comprising a lever of substantially U-shape in cross section and having an end formed with a bifurcated jaw adapted to 15 span the valve stem and to be inserted between the helices of a spring, in combination with a resilient latch permanently secured to the inner and upper face of the web of said lever and formed with a rounded forward downwardly presented 20 hook portion at its forward end extending across a portion of said bifurcated jaw, said hook portion being adapted to ride up over and drop down behind a helix of the spring to hold said helix between the opposing faces of said jaw and said 25 latch, a stop pin extending across the channel in said lever slightly to the rear of said jaw, a wedge block mounted for reciprocation between said latch and pin and adapted to be moved to a position wherein it engages said stop pin with the 30 rear upper portion of its wedge face and engages said latch adjacent said hook portion, and means for reciprocating said wedge block.

3. A valve spring lifter comprising a lever having an end formed with a bifurcated jaw, in combination with a latch mounted on said lever and formed with a rounded forward downwardly presented hook portion at its forward end extending across a portion of said bifurcated jaw, a wedge block mounted for movement with relation to 40 said latch, means limiting the movement of said wedge block in a direction perpendicular to said latch, and means for moving said wedge block at will to any one of several positions.

4. A valve spring lifter comprising a lever having an end formed with a bifurcated jaw, in combination with a latch mounted on said lever and formed with a rounded forward downwardly presented hook portion, a wedge block mounted 50 for movement with relation to said latch and means for limiting the movement of said wedge

block in a direction perpendicular to said latch in one operative position of said wedge block.

5. A valve spring lifter comprising a lever having an end formed with a bifurcated jaw, in combination with a latch mounted on said lever and formed with a rounded forward downwardly presented hook portion and means for preventing the movement of said hook portion in a direction away from the opposed face portion of said jaw, whereby an element interposed between said jaw and said latch to the rear of said hook portion may be securely held thereby. 5

6. A valve spring lifter comprising a lever having an end formed with a bifurcated jaw, in combination with a latch mounted for movement 15 on said lever and adapted to grip between it and said jaw an interposed portion of a valve spring, and means for preventing movement of said latch away from the opposed face of said jaw when a portion of a valve spring is interposed between 20 said latch and said jaw.

7. A knock-down pry bar lever valve spring lifter comprising two separable sections of substantially equal length and substantially U-shape in cross section, one of said sections having its 25 forward end portion formed with a bifurcated jaw, and having its extreme rear end portion formed with a pair of transversely registering longitudinally extending slots, and the other section having its forward end portion inwardly 30 offset to be received in the rear portion of the first section and having its extreme forward end portion formed with a pair of transversely registering longitudinally extending slots, in combination with a pair of plates movably attached to 35 the respective sides of the rear portion of said first section and secured to each other below said section, the extreme rear portions of said plates being slotted vertically to intersect the slots in said first section, a pivot pin extending through 40 said plates and the sides of said first mentioned section and normally being received in the slots in said second section, a pin passing through the walls of said second section and adapted to be received in the slots in said plates and said first section, and yielding means for holding the plates in normal position with their vertical slots intersecting the slots in the rear portion of said first section to lock said pin therein. 45
